(57) **CLAIM**

An ornamental design for a wheel flange, as shown and described.

DESCRIPTION

FIG. 1 is a rear perspective view of the wheel flange; FIG. 2 is a front perspective view of the wheel flange; FIG. 3 is a rear elevational view of the wheel flange; FIG. 4 is a top plan view of the wheel flange; FIG. 5 is a right side elevational view of the wheel flange; FIG. 6 is a front elevational view of the wheel flange; and, FIG. 7 is a side cross-sectional view of the wheel flange, for clarity of disclosure, taken at Line 7-7 shown in FIG. 3. The broken lines shown illustrate portions of the wheel flange that form no part of the claimed design.
